UNITED STATES PATENT OFFICE.

SANDOR OSZE, OF MARTINS CREEK, PENNSYLVANIA.

MECHANISM FOR ASCENSION AND DESCENSION.

1,358,325.

Specification of Letters Patent.

Patented Nov. 9, 1920.

Application filed November 4, 1919. Serial No. 335,731.

To all whom it may concern:

Be it known that I, SANDOR OSZE, citizen of Hungary, and resident of Martins Creek, in the county of Northampton and 5 State of Pennsylvania, have invented certain new and useful Improvements in Mechanism for Ascension and Descension, of which the following is a specification.

This invention relates to mechanism for 10 ascending and descending relatively to a supporting point, and is especially applicable to construction scaffolds and balloons within the limits of the mechanism.

The object of this invention is the provision 15 of a mechanism which may readily be carried by the work-scaffold or balloon basket and which is operable therefrom for the purpose of ascending and descending for comparatively short vertical distances.

20 A further object of this invention is to keep the balloon basket or scaffold on which it is used level during the raising and lowering thereof.

The landing of a balloon has heretofore 25 been accomplished usually with the aid of persons on the ground because of the difficulty of accurate management of the balloon vertically. By means of my invention it is possible to make safe landings from balloons without outside help.

30 My mechanism can also be used to advantage in connection with captive war observation balloons. In cases where the hawser of the captive balloon breaks, it 35 has been necessary for the observer to leave the basket or carriage and escape by means of a parachute; the balloon and basket containing valuable instruments and maps often being lost by being blown over the enemies' lines. By means of my invention, the observer can lower himself to the ground, thereby saving not only his life, but the maps, instruments and the balloon itself.

45 The use of my invention on work scaffolds provides a safe and rapid means for raising and lowering the same controllable from within the scaffold, which is kept level during the raising and lowering operations.

50 For the attainment of the aforesaid objects and advantages, I employ the mechanism shown in its preferred form in the accompanying drawings, in which;

55 Figure 1 shows an elevation of my improved mechanism, as it appears, when attached to a balloon basket.

Fig. 2 is an isometric drawing of that part of my mechanism which is attached to the basket or carriage and.

Fig. 3 is a side elevation of the same. 60

In the practical embodiment of my invention, the hanger or supporting bracket 1, has mounted therein pulley 2, said hanger being shown at Fig. 1 supported or hung by the usual balloon ropes 13 from balloon 12, 65 though it is obvious that the hanger 1 may be supported in any desired manner, as from the roof of a building.

A balloon basket, scaffold or carriage 8 is supported from hanger 1 by means of a suitable wire or rope cable 3, which passes over pulley 2 and around pulley 5. Said pulley 5 is mounted on shaft 14 which is supported in bearings 6, which are in turn mounted on one end of said carriage 8. The other end 70 of said carriage carries bearings 7 which support shaft 16, said shaft carrying drum 4, about which the ends of cable 3 are attached and partly wound. Pulley 15 on the end of shaft 16 is driven by means of any 75 suitable source of power as by motor 11 through belt 10. Said motor may be supported by a bracket as 9 and current supplied by a storage battery not shown.

When it is desired to make a landing from 80 a balloon (Fig. 1) current is supplied to motor 11 to rotate it in the proper direction to unwind cable 3 from drum 4. Said cable is thereby loosened, the weight of the carriage being sufficient to take up the slack as 85 it develops, thereby gradually lowering the carriage. The entire operation is readily controllable at will from the operator's position in the carriage, which finally reaches 90 a lower position as shown by the dotted lines 95 in Fig. 1.

To raise the carriage, the motor is rotated in the opposite direction, whereby cable 3 is wound around drum 4 and shortened, thereby raising the carriage toward hanger 100 1. If said carriage is used as scaffold, and the hanger 1 is supported from the roof or side of a building, the raising and lowering of the carriage is accomplished in the same manner. 105

It is obvious that said carriage will remain level during the raising and lowering operations since the same amount of cable is drawn in and paid out on both sides of pulley 2 during said operations. 110

The various operating parts such as the motor and pulley are so proportioned as to

prevent the weight of the carriage and its contents from causing the drum to unwind when motor is not running.

What I claim is:

- 5 1. In a mechanism of the character described, a carriage, a cable for supporting said carriage, and means carried by said carriage, for raising and lowering said carriage comprising a pair of shafts arranged at opposite ends of said carriage, a pulley on one of said shafts, and a drum on the other of said shafts, said supporting cable passing around said pulley and back around said drum.
- 15 2. In a mechanism of the character described, a carriage, a hanger from which said carriage is supported, a pulley mounted in said hanger, a pulley mounted at one end of said carriage, a drum mounted at the other end of said carriage, a cable attached to said drum and passing around both of said pulleys and means for rotat-

ing said drum for winding and unwinding portions of said cable whereby said carriage is raised and lowered relatively to said hanger. 25

3. In a mechanism of the character described, a carriage, a hanger, from which said carriage is supported, a pulley mounted in said hanger, a pulley mounted at one end of said carriage, a cable attached to said drum and passing around said drum and both of said pulleys, and means for rotating said drum for winding and unwinding equal portions of said cable on each side of said hanger pulley whereby the level position of said carriage is maintained, while said carriage is raised or lowered. 30 35

Signed at Martins Creek, in the county 40 of Northampton, and State of Pennsylvania, this 28th day of October, A. D. 1919.

SANDOR OSZE.
